UNITED STATES PATENT OFFICE.

JOSEPH E. TRUITT AND EMIL ACKERMAN, OF CHICAGO, ILLINOIS.

SHUTTER.

1,251,593.

Specification of Letters Patent.

Patented Jan. 1, 1918.

Application filed July 2, 1917. Serial No. 178,094.

To all whom it may concern:

Be it known that we, JOSEPH E. TRUITT and EMIL ACKERMAN, both citizens of the United States, residing at Chicago, in the 5 county of Cook and State of Illinois, have invented certain new and useful Improvements in Shutters, of which the following is a specification.

This invention relates to ventilating fans 10 and particularly to the arrangement of the shutters whereby the openings in the wall of buildings in which these ventilating fans are installed are closed or opened in accordance with the flow of air under the control of the fan or blower.

An object of the invention is to provide a shutter with a plurality of vanes which are pivotally mounted in the wall opening, the pivot pins of these vanes being arranged 20 slantingly with respect to a vertical plane containing the axis of the shutter opening, and with respect to a plane parallel to the plane of the opening itself.

Another object of the invention is to provide in a shutter mechanism vanes, which, while being inclined to drop into closing position, will not exert an excessive resistance against an opening movement caused by a flow of air directed from one side 30 against the vanes.

Another object of the invention is to provide vanes which, when in opened or partly opened position, will occupy a dihedral angle with respect to the plane of opening, 35 and thereby afford a better passage of the air from the interior of the building outwardly than with parallel vanes which partly overlap each other and which are arranged so as to swing transversely with 40 respect to said opening.

Another object of the invention is to combine with a frame structure for the vane supports, a flange or wall confining an opening of polygonal contour, in which opening 45 the vanes are mounted. The edges of the vanes also will be formed by straight lines, which arrangement facilitates the manufacture of these vanes.

Another object of the invention is to combine with this structure presenting an opening of a polygonal area, another opening of circular area and surrounded by an annular portion of the structure so as to facilitate the introduction of the frame structure into the wall of the building.

It is also an object of the invention to

combine with a frame structure of this character a bridge or web, spanning the opening for the vanes and on which the mechanism for actuating the vanes simultaneously is mounted, whereby the leverage of the arms for directing the various vanes to open or closed position is considerably shortened as compared with that construction in which a common arm for all of the vanes is disposed at one side of the same.

With these and other objects in view, embodiments of the invention are described in the following specification, and the novel features of the same are pointed out in the appended claims, reference being made to the accompanying drawing, wherein—

Fig. 1 is a rear view of a frame structure showing the vane supports and vanes in combination with the shutters and the mechanism for actuating the various vanes.

Fig. 2 is a sectional view through the shutter controlling mechanism and the support for said mechanism, on a larger scale than shown in Fig. 1.

Fig. 3 is a view of the frame structure as seen from the side opposite the side from which it is viewed in Fig. 1.

Fig. 4 is a partial longitudinal sectional view to illustrate the frame structure, the vanes, and their supports; the actuating mechanism not being illustrated in this figure.

Fig. 5 is a similar sectional view of the frame structure in combination with slightly modified portions of a wall in which said frame structure is inserted.

Fig. 6 is a partial sectional view, similar to Fig. 4, showing a larger portion of the frame structure inserted in the opening of a wall.

Fig. 7 is a front view of a modified frame structure similar to the view illustrated in Fig. 3.

Fig. 8 is a partial sectional view through the support for the vane controlling mechanism of the modified structure illustrated in Fig. 7, showing the vanes in closed position.

Fig. 9 is a similar sectional view showing the vanes partly opened, and

Fig. 10 is a detail view, partly in section and partly in elevation, showing a pivotal support for a vane.

In most of the known shutter mechanisms for ventilating or exhaust fans, the various vanes were pivotally mounted on horizontal rods in a frame structure, so as to have a

tendency to remain in partly overlapping closed position; they were operated by a separate motor which served for opening the same. In the present structure the vanes 5 are pivoted about axes which are nearly vertical, but which slant inwardly and downwardly with respect to a vertical axial plane and with respect to the plane of the opening, so as to facilitate closing motion of the vanes. 10 This arrangement, however, will permit the vanes to be readily opened under the influence of the air flowing against the vane in a predetermined direction. Owing to this construction of downwardly slanting, pivotal axes, the vanes are inclined to be closed normally, but they do not resist with their full weight the force of a draft of air directed against the same, so that they can be moved to opening position easier than if 15 20 they would be pivoted about a horizontal axis.

The embodiment of the invention illustrated in Figs. 1 to 6 inclusive comprises a frame structure 11 preferably of cast metal 25 and having an outer circular flange 12 provided with openings 13, whereby this frame structure may be fixed to the wall of the building by suitable lag-screws 14 or the like. A proper fit of the frame structure in the 30 opening of the building wall 15 is attained owing to the provision of an annular flange or bead 16 projecting, in the embodiment illustrated in Fig. 4, toward the building and facilitating the cementing of the cast metal 35 frame 11 to the wall of the building. Another relatively heavy flange 17 projecting from the circular plate or flange 12 in a direction opposite to that of the flange or bead 16 has, in the embodiment shown, an outer 40 circular circumference, indicated at 18, and a polygonal internal perimeter, as indicated at 19. A circular flange 20 projects from the flange 12 inwardly and confines the circular 45 exhaust opening 21. The edges of the vanes 25 are (when the vanes are closed) parallel with and adjacent to the polygonal circumference 19 of the flange 17, and are therefore also straight edges, but they may consist of broken lines, for instance, as indicated at 50 50, 31 in Fig. 3.

A member 22 substantially vertical, spans the opening confined by the polygonal line 19, and this bridge or web 22 preferably is inclined with respect to a plane defined by 55 the front or rear surface of the frame structure, so as to have its lower end at a greater distance from the inner surface of the frame structure than the upper end. As shown in Fig. 3, this web or bridge 22 also is of different width at its two ends, the width gradually decreasing from the upper end toward the lower end. The two lateral edges 23 of the bridge have equal inclination with respect to the longitudinal central line of the 60 bridge. Between its ends the bridge 22 is

provided with an enlargement or hub 24 which serves for supporting the mechanism whereby the vanes may be opened or closed simultaneously.

The various vanes 25 are supported in this 70 frame structure on pivots 26, the axes of which are substantially parallel to the lateral edges 23 of the central web or bridge, so that these vanes also are arranged slantingly with respect to a plane parallel to the 75 plane of the frame opening and with respect to a vertical plane. The pivots 26 are inserted in suitable passages 27 in opposite portions of the flange 17, and may be held therein in any suitable way. The vanes 25 preferably are constructed of light, non-corrosive sheet metal, and are turned at one of their longitudinal marginal portions so as to form sleeves 28 which surround the pivots, whereby upon a movement of air directed against 80 the inner surface of these vanes the latter will be swung about their pivots to discharge the air through the circular opening 21 of the structure.

For the purpose of controlling the vanes 90 on both sides of the bridge with each movement of any vane on either side thereof a double-armed lever 33 is rotatably mounted at the inner end of the hub 24 projecting from the member 22. The free ends of this 95 double-armed lever 33 are movably connected with the vanes at the right side and at the left side of the web 22 through a plurality of links 34, 35 which in their turn are flexibly connected with brackets 36 rigidly attached to surface portions of the 100 vanes 25.

If air is directed, for instance, toward the surface of the vanes at the left hand side of the central web 22, as shown in Fig. 2, 105 the vanes will be swung about their pivotal supports which slant laterally and rearwardly, and owing to their movable connections 36, 35, 34 with the arms of the central lever 33, said central lever will be turned 110 about its pivot; this rotation of the central lever will cause a swinging motion of the other links 34, 35 connected therewith, and this motion will be transmitted to the vanes 25 on the right hand side of the web 22. 115 When the vanes at opposite sides are swung about their pivots, symmetrically located vanes will form a dihedral angle with respect to the plane of the opening 21.

According to Fig. 5, the frame structure 120 is arranged similar to the arrangement shown in Fig. 4. An additional sill 40, however, is added to the wall 15 in which the frame structure 11 is supported. This sill may then serve to hold a screen 41 or 125 the like to prevent injury to the shutter mechanism.

The modification illustrated in section in Fig. 6 is distinguished from the embodiment of the invention described and shown with 130

reference to Figs. 1 to 4 by the fact that the supporting flange 17 for the vanes is inserted into the opening of the wall 15 instead of being arranged on the outside thereof, thus providing a firmer support for the frame structure 11 in the wall itself. In other respects this construction is similar to the first described embodiment.

In the modification illustrated in Figs. 7, 8, and 9, the inner edge of the flange 17 on the frame structure is octagonal, as shown at 42, and the edges of the vanes 25' are shaped correspondingly. It will be seen that instead of having three vanes 25 at each side of the web 22', as shown in Figs. 1 and 3, in this modification two vanes 25' are only arranged at each side thereof, the support of these vanes in the frame structure 11' being similar to the support disclosed with respect to Figs. 5 and 6. In this instance also the actuation or oscillation of the vanes 25' at both sides of the web 22' is effected by a lever 33' which is connected flexibly with brackets 36' rigidly attached to the several vanes. Upon oscillation of one of the vanes about its pivotal axis, a similar oscillating movement is imparted through the link 45 connecting this vane with the next vane. A corresponding movement is then transmitted to the vanes 25' at the other side of the bridge 22' through the lever 33' which is rotatably mounted in the web.

The brackets 36' attached to the vanes 25' in this modification are twisted about their longitudinal axis, so as to reinforce this rigid connection between the movable links 45 and the vanes. It will also be seen that the inner vanes have their free edges 40 slightly offset, so as to form a bead 46, which, when the vanes are in closed position, overlies the pivotal sleeve 28' of the adjacent vane 25' and thereby effects a closure of the entire shutter opening when the blower is 45 inoperative.

Instead of providing pivot pins which pass from one side of the polygonal flange to the other side thereof, this pivotal connection may also be provided, as shown in Fig. 10, merely by inserting a screw 47 having an extension 48 at its lower end through a portion of the flange 17. The pivotal friction is thereby reduced considerably, and owing to the alinement of these screws at 55 opposite points of the flange (not shown) a satisfactory pivotal support is attainable. The removal of any vane for the purpose of repair or exchange is facilitated, as it is then only necessary to withdraw one of the screws 47 on which the sleeves 26 of these vanes are supported.

We claim:

1. A shutter mechanism for ventilating fans, comprising in combination with a frame structure having a shutter opening,

a plurality of oscillatory vanes located when in closed position in a plane slanting with respect to the plane of said opening, and a plurality of pivotal supports for said vanes permitting a swinging movement of the 70 same about lines inclined with respect to other of said lines and with respect to a vertical line across said opening.

2. A shutter mechanism for ventilating fans, comprising in combination with a frame structure having a shutter opening, a plurality of vanes, and pivotal supports for said vanes adapted to maintain the axes of oscillatory movement of said vanes slanting with respect to the plane of the opening 80 and with respect to a central vertical plane through said opening.

3. In a shutter mechanism for ventilating fans, the combination with a frame structure having an annular flange with an inner 85 polygonal circumference, oscillatory vanes having their edges adjacent to and parallel with the circumferential lines of said polygonal opening, and pivots for supporting the vanes with their axes of oscillation in 90 a downwardly and outwardly slanting direction.

4. In a shutter mechanism for ventilating fans, the combination of a frame structure having a polygonal portion confined by a 95 flange, a plurality of vanes symmetrically disposed with respect to a central line connecting directly opposite portions of the said flange, pivots slanting from an upper portion of said flange to a lower portion thereof, the vanes being mounted on said pivots, and means for imparting symmetrical movement to symmetrically located vanes.

5. In a shutter mechanism for ventilating 105 fans, the combination of a frame structure having a shutter opening and polygonal flange, a bridge spanning said flange, a plurality of vanes located on each side of said bridge and adapted to close the said opening, a plurality of pivots extending in slanting direction from upper and inner portions of the flange to lower and outer portions of the same, and means for transmitting motion of a vane from one side of said bridge 110 to the symmetrically located vane on the other side of said bridge.

6. In a shutter mechanism for ventilating fans, the combination of a frame structure having a polygonal flange surrounding a 120 shutter opening, a bridge spanning said opening and slanting in direction from the inner surface of the frame structure outwardly, a plurality of vanes located in the plane of said bridge, and a plurality of 125 pivots inclined laterally and outwardly supporting said vanes.

7. In a shutter mechanism for ventilating fans, the combination of a frame structure having an opening, a bridge slanting in di- 130

rection from the inner surface of said frame structure to the outer surface of the same and spanning the opening in vertical direction, the lateral edges of the bridge converging downwardly, a plurality of vanes, and pivots supporting said vanes, the pivots on each side of said bridge being parallel to the lateral edge to which they are adjacent.

10. 8. In a shutter mechanism for ventilating fans, the combination of a frame structure having an opening surrounded by a flange, a bridge spanning said opening from above downwardly and slanting from the inner plane of the flange toward the outer plane, vanes arranged at both sides of the bridge, pivots for said vanes slanting in the same direction as the bridge and at the same time slanting from above downwardly in direction toward the axis of the bridge, said vanes being mounted on said pivots, and means mounted on the bridge for transferring a movement of one of said vanes to the other vanes.

20. 9. In a shutter mechanism for ventilating fans, the combination of a frame structure having a central opening surrounded by a flange which has a circular circumference and a polygonal inner circumference, a bridge spanning said opening and slanting from one plane of the flange toward the other plane thereof, the edges of said bridge converging downwardly, pivots mounted on each side of the bridge in the said flange, vanes loosely supported on said pivots and overlapping each other, a central hub on said bridge, a lever rotatably mounted on said hub, and links connecting the ends of said lever with several vanes, whereby move-

ment of one of said vanes is transmitted to another vane.

10. In a shutter mechanism for ventilating fans, the combination of a frame structure having a central opening surrounded by a flange which has a polygonal inner circumference, a bridge spanning said opening and slanting from one plane of the flange in direction toward the other plane thereof, a plurality of pivots supported in said flange, a plurality of vanes supported by said pivots and slanting in a direction parallel to the slant of the bridge, a double-armed lever centrally pivoted on the bridge, and brackets rigidly attached to the vanes, and links connecting said brackets with each other and with the lever on the bridge.

11. In a shutter mechanism for ventilating fans, the combination of a frame structure having a central circular opening surrounded by a flange which has a circular outer circumference and an octagonal inner circumference, a bridge spanning said opening and slanting in direction from one plane of the flange toward the other plane of the same, said bridge being provided with converging lateral edges, two pivots at each side of said bridge and extending in a direction parallel to the lateral edge of the bridge near which they are located, vanes loosely supported on said pivots, brackets rigidly attached to the vanes, links connecting said brackets, a double-armed lever pivotally mounted on the bridge, and links connecting free ends of said lever with the first mentioned links.

JOSEPH E. TRUITT.
